UNITED STATES PATENT OFFICE.

EMILE LECOULTRE, OF ALEXANDRIA, VIRGINIA, ASSIGNOR TO CHARLES C. CARLIN, OF ALEXANDRIA, VIRGINIA.

TABULATING DEVICE FOR TYPE-WRITING MACHINES.

No. 858,082.

Specification of Letters Patent.

Patented June 25, 1907.

Application filed March 26, 1904. Serial No. 200,114.

To all whom it may concern:

Be it known that I, EMILE LECOULTRE, a citizen of the Republic of France, residing at Alexandria, in the county of Alexandria, State of Virginia, have invented certain new and useful Improvements in Tabulating Devices for Type-Writing Machines, of which the following is a description, reference being had to the accompanying drawing and to the letters and figures of reference marked thereon.

My invention relates to tabulating devices for typewriting machines, and is particularly adapted for use in connection with typewriting machines of what is known as, the Remington type.

The object of the invention is to provide in simple and efficient form devices adapted to be attached to a typewriting machine, or used in connection therewith, for tabulating work. While the invention is particularly intended to be so constructed that it may be readily attached to and detached from a typewriting machine, without change of such machine in any manner, it may also be constructed as a permanent part of such machine.

A further object of my invention is to provide a device for tabulating purposes, in which by single operation of a key, the carriage is released and brought to a stop in proper position to print the first figure of the number to be written, so that units of the same order shall be in the same vertical line.

With these objects in view my invention consists in the construction hereinafter described and claimed.

Referring to the drawings, Figure 1 is a top plan view of a typewriting machine having my invention applied to it; Figs. 2 and 3 are side views of the typewriting machine taken from opposite sides; Fig. 4 is a side view partly in section showing the stop carried by the carriage; Fig. 5 is a perspective view of the stop carried by the carriage; Fig. 6 is a detail view of the differential device; Fig. 7 is a detail view of the notched bar of the differential device; Fig. 8 is a plan view of the differential device; Fig. 9 is a detail view partly in section showing a modified form of stop bar; Fig. 10 shows the stop bar and stop in cross section and side view, and Fig. 11 shows the stop bar and washers in cross section and side view. Fig. 12 is a de-

tail perspective view of the lever which transmits longitudinal movement to the tabulating stop bar.

Various parts are omitted or broken away in some of the views for the sake of clearness.

Referring to the parts by reference number, 1 is the frame of a typewriting machine of the Remington type; 2 is one of the printing keys; 3 is the carriage; 4 the carriage rail; 5 the pinion of the escapement, and 6 the rack bar carried by the carriage; 7 is the rearwardly extending arm connected with the rack which, in the typewriting machine, is arranged to come in contact with marginal stops carried by the stop bar; 8 are the lugs extending upward from the top plate of the machine in rear of the carriage, which, as the machine is ordinarily arranged, support the stop bar and guide rod 8' (Fig. 2). The construction so far described is that of the typewriting machines, of the ordinary Remington type and are shown only so far as is necessary to enable the construction and arrangement of my invention to be understood. It will be understood that the pinion 5 is part of the carriage feeding mechanism common to the Remington machine and that said carriage feeding mechanism is operable in a known manner by the printing keys 2 to feed the carriage a letter space distance at a time in printing direction.

Instead of the clamps ordinarily employed for holding the ends of the guide rod in position on the lugs 8, I employ brackets 10 having in their upper ends bearings 11, in which is mounted a tabulating stop bar 12, the construction being such that the stop bar 12 may be slid lengthwise in its bearings but may not be rotated therein. This bar may be a notched bar of ordinary form adapted to receive column stops 13 as shown in Fig. 4. I prefer, however, to use a column stop bar and stops of the construction indicated in Figs. 9, 10 and 11, in which the bar 12 is circular in cross section with ends of less diameter than its main portion with a wide longitudinal notch 12', formed from end to end of the main portion of the bar. On the main portion of the bar are mounted a series of stops 13' arranged to have a limited movement of rotation on the stop bar to bring their projections 13'' into and out of operating position. This rotary movement is limited by means of an inwardly projecting lug

13³ which extends into the notch 12', so that the sides of the notch serve as abutments to prevent the stops from being rotated except through an arc determined by the width of 5 the notch carried on the stop bar. Between the stops and alternating with them throughout the length of the stop bar are placed non-rotary washers 14 having inwardly projecting lugs 14' which are made of the full width 10 of the notch, thus preventing the possibility of these washers turning on the stop bar.

Secured to the rearwardly extending arm 7 is a rearward extension 15 preferably having its rear end bent over, as indicated at 15'. 15 A coupling member or clamp 15² C-shaped in cross section and carrying a clamping screw 15³ may be employed to secure the extension 15 to the arm 7. The coupling member is first arranged to embrace the overlapping 20 portions of the arm 7 and extension 15, and then the screw 15³ may be tightened to clamp the parts together. Secured to the rear bar of the carriage 3 is an arm 16 carrying a movable stop 17. This movable stop 25 17 is pivoted at 18, to the arm 16 and is provided in its head with a slot 19 through which pass headed screws 20 which secure it to the arm 16 and permit it to be turned on its pivot to bring its rear end into position to strike a column stop carried by the stop bar 12. The 30 stop has a rearwardly extending arm 21 preferably with its end bent over, as shown at 21'. A spring 22 secured at one end to the arm 16 and at its free end bearing against the rearwardly extending arm 21 serves to 35 hold the stop 17 normally out of position to engage a column stop.

It will be understood that the extension 15 may be formed integrally with the arm 7 if 40 preferred and the arm 16 carrying the movable stop 17 may be formed on or permanently secured to the back bar of the carriage. In order to adapt my invention for attachment to machines now in use the extension 15 and the arm 16 are made detachable and the arm 16 is arranged to be adjusted by means of a slot 16' and screws 16² by 45 which it may be secured to the back bar of the carriage.

50 It will be understood that the depression of the rear end of the arm 21 will cause the stop 17 to be moved into position to contact with the stop 13 and the depression of the rear end of the extension 15 will raise the rack bar 6 out of contact with the pinion 5 to release the carriage and permit it to be carried forward by its feed mechanism until stopped by the stop 17 striking a column stop.

60 For the purpose of effecting the depression of the rear end of the arm 21 and the depression of the rear end of the extension 15, I provide a rocking member comprising a rod 24 carried by arms 25 and 26 pivoted to the 65 brackets 10, said rod being adapted to be

moved eccentrically about the pivots of the arms 25 and 26. Said pivots are designated respectively by the numerals 25' and 26'. It will be noted that the bar or rod portion 24 of the rocking member does not turn about its own longitudinal axis but turns about an axis which passes through the pivots 25' and 26'. The bar or rod 24 may therefore be said to be an eccentric part, that is, a part arranged externally or eccentrically of or away from the axis about which it turns. The left hand arm 26, as shown in Fig. 3 has a forward and downward extension 26² to the end of which is pivotally connected the upper end of an arm 27', the lower end of 80 which is adjustably connected to a bar 27 extending from side to side of the machine and pivotally connected at its ends to arms 28 pivoted at their opposite ends to clamps 29 secured to the sides of the frame 1.

In typewriting columns of numbers it is, of course, essential that units of the same order shall come in the same vertical line and the first figure of the number to be written may belong to the units, tens, hundreds, or other line. It is desirable in order that units of the same order may be written in proper line that the column stop should be so placed that it shall determine the position of the decimal point if numbers indicating dollars and cents are to be written or the lowest order of units, if numbers not indicating dollars and cents are to be written. In order to provide for writing the first figure of the number to be written, in proper position relative to the column stop, I have provided means for shifting the position of the stop bar and the column stops carried thereby. The means which I have provided for this purpose comprises a series of differential keys 30, preferably arranged in front of the key board and marked respectively 0, 1 (units), 10 (tens), 100 (hundreds), 1,000 (thousands), 10,000 (ten thousands), 100,000, (hundred thousands), 1,000,000 (millions). These keys 105 are pivoted on a shaft 31 carried by clamps 32 secured to side of the frame 1 and are held in normal position by springs 33 secured to a bar 34 carried by clamps 35 secured to the sides of the frame 1. The key levers of the keys are arranged to be fitted between the key levers of the keys 2 of the key board of the machine and their rear ends 30' are arranged to move up and down in slots formed in the outer plates of the differential device. 115

120 The differential device comprises a fixed and a movable member, the movable member being arranged to be acted on by the differential keys being so connected to the tabulating stop bar that by its movement 125 the stop bar will be moved to the right, that is in a direction opposite to the direction of feed of the carriage, a distance depending upon the differential key operated in order to stop the carriage in proper position for 130

printing the first figure of the member to be written.

The fixed member of the differential mechanism consists preferably of a pair of parallel plates 40 suitably spaced apart to carry a sliding plate 41 between them and guide it in its movement. The plates 40, or one of them, are secured by clamps to the frame of the machine and are provided with slots 42 at right angles to the longitudinal line of the plates which are adapted to receive and guide the ends 30' of the differential keys. The sliding plate 41 is provided with a series of differential slots 43 each having one side at right angles to the longitudinal line of the plate and the opposite side inclined at such angle that as the end of the key levers of the differential keys are forced into the slots 42 they will act upon the sliding plate to cause it to move a distance depending upon the particular key operated and the inclination of the side of the slot 43 into which the end of the lever of that key enters. A slot 44 with both sides at right angles to the longitudinal line of the plate is provided as shown in Fig. 7, at the right of the figure into which the end of lever of the zero key enters.

The sliding plate 41 is pivotally connected preferably at the right of the machine, to a lever 45 pivoted at 46 to a plate 47 secured by a removable clamp or otherwise to the frame of the machine. This lever 45 is bent or curved as indicated in Fig. 2 so as to extend above the plate of the machine, preferably passing upward beyond the outer edge of the top plate, and at its upper end is provided with a slot 48 through which a pin or screw 49 extends connecting the end of the lever with the tabulating stop bar. It will thus be seen that movement of the sliding plate 41 through the lever 45 transmits movement to the tabulating stop bar in a direction opposite to the direction of feed of the carriage, the extent of this movement being determined by the movement given to the sliding plate.

A spring 50 preferably connected to the lever 45 serves to hold the lever, the sliding plate and the stop bar in normal position.

The bar 27 extends across the machine above the rear ends of the key levers of the differential keys so that as one of these keys is operated the bar 27 will be lifted, and through the arm 27' and arm 26 will cause the rod 24 to be depressed, pressing down the end of the extension 15 and simultaneously pressing down the end of the arm 21, thus raising the rack bar 6 to release the carriage from the escapement mechanism and causing the end of the movable stop 17 to be brought into operative position to engage a column stop. During this movement the spring 22 resists the depression of the arm 21 and thus causes it to act on the rod 24 as a brake to retard the carriage after the latter has been

freed from the escapement or letter space feeding devices. If the zero key is operated no movement will be given to the sliding plate or the stop bar, the operation of the key serving only to effect the release of the carriage and move the end of the movable stop into position to engage the column stop. As soon as the differential key is released the rack bar drops into engagement with the pinion of the escapement mechanism and the movable stop is returned to normal position by its spring 22 permitting the carriage to be fed forward as the keys of the typewriting machine are operated. If one of the differential keys, other than the zero key, is operated its end 30' as it enters and passes upward in its slot 42 will, by its action on the inclined side of its slot 43 in the sliding plate, cause the sliding plate to move to the left which through the lever 45, will cause the stop bar to move to the right to move the column stop one, two or more spaces to the right according to the differential key operated so that the carriage will be stopped by the contact of the movable stop 17 with the column stop in proper position to print the first figure of the number to be written.

It will be noted that the shaft on which the differential keys are pivoted, the bar carrying the springs which hold these keys in normal position, the fixed plate of the differential mechanism, the arms which carry the bar on which differential keys act to effect the release of the carriage and the movement of the movable stop, as well as the lever which connects the sliding bar of the differential mechanism to the stop bar, are all arranged to be secured to the frame of the machine by removable clamps, and the extension 15 and the arm which carries the movable stop are also each arranged to be secured in position by clamps, so that all of these parts may be secured in position without the necessity for in any way making any change in a typewriting machine as constructed for ordinary typewriting, and the stop bar brackets 10 may be secured in place without other change than the mere removal of the screws which hold the guide bar in position, these brackets when secured in position serving to hold the guide bar in place. The device is thus adapted to be attached to machines in use with very little trouble and without requiring special skill.

Of course if desired the various parts above described as held in place by removable clamps may be permanently secured in place.

The spring 22 is preferably of such strength as to press the end of the arm 21 firmly upward so as to offer considerable resistance to the depression of this arm by the rod 24 so that when this rod is depressed there will be considerable friction between it and the end of the arm; thus braking or

5 checking the movement of the carriage when released from the escapement mechanism and preventing the shock which would otherwise result from the release of the carriage and the momentum with which its movable stop would be brought against the column stop.

10 I do not desire to be limited to the precise form and arrangement above described as it is obvious that changes in form and arrangement may be made and the invention may be adapted to other styles of writing machines besides the one illustrated without departing from the spirit of the invention.

15 Having thus described my invention, what I claim as new and desire to secure by Letters Patent is:

1. In a typewriting machine, the combination of the frame, a longitudinally movable stop bar provided with a column stop mounted on the frame, means for moving the stop bar longitudinally, a carriage mounted to travel along the frame, an escapement mechanism carried by the frame for controlling the feed of the carriage, means for releasing the carriage from the escapement mechanism, a movable stop on the carriage normally out of line with the column stop, means for moving the movable stop into position to engage the column stop, and a key arranged to simultaneously operate the means for moving the stop bar, the means for releasing the carriage from the escapement mechanism and the means for moving the movable stop into position to engage the column stop.

2. In a typewriting machine, the combination of the frame, a longitudinally movable stop bar provided with a column stop mounted on the frame, means for moving the stop bar longitudinally, a carriage mounted to travel along the frame, an escapement mechanism carried by the frame for controlling the feed of the carriage, means for releasing the carriage from the escapement mechanism, a movable stop on the carriage normally out of line with the column stop, means for moving the movable stop into position to engage the column stop, and a series of keys arranged to simultaneously operate the means for moving the stop bar, the means for releasing the carriage from the escapement mechanism and the means for moving the movable stop into position to engage the column stop.

3. In a typewriting machine, the combination of the frame, a longitudinally movable stop bar provided with a column stop mounted on the frame, differential means for moving the stop bar longitudinally, a carriage mounted to travel along the frame, an escapement mechanism carried by the frame for controlling the feed of the carriage, means for releasing the carriage from the escapement mechanism, a movable stop on the

carriage normally out of line with the column stop, means for moving the movable stop into position to engage the column stop, and a series of differential keys arranged to simultaneously operate the means for moving the stop bar, the means for releasing the carriage from the escapement mechanism and the means for moving the movable stop into position to engage the column stop.

4. In a typewriting machine, the combination of the frame, a longitudinally movable stop bar provided with a column stop detachably mounted on the frame, means for moving the stop bar longitudinally, comprising differential mechanisms secured to the frame, a carriage mounted to travel along the frame, an escapement mechanism carried by the frame for controlling the feed of the carriage, means for releasing the carriage from the escapement mechanism, a movable stop detachably secured on the carriage normally out of line with the column stop, means for moving the movable stop into position to engage the column stop, and a series of keys detachably connected to the frame arranged to simultaneously operate the differential mechanism for moving the stop bar, the means for releasing the carriage from the escapement mechanism and the means for moving the movable stop into position to engage the column stop.

5. In a tabulating device for use in connection with a typewriting machine, a stop bar mounted on the frame and provided with a column stop, a movable stop on the carriage having a rearwardly extending arm and normally out of position to engage the column stop, a swinging rod adapted to depress the rearwardly extending arm to move the movable stop into position to engage the column stop, and a spring acting to resist the depression of the rearwardly extending arm and thus cause it to act as a brake, and means for releasing the carriage.

6. A stop bar for tabulating machines comprising a bar circular in cross section having a longitudinal groove formed therein, and a stop mounted to rotate on the bar provided with a lug adapted to enter the longitudinal groove, but of less width than the width of the groove, the lug being integral with said stop and operative to limit positively the rotary movement of said stop on said bar.

7. A stop bar for tabulating machines comprising a bar, a series of stops having limited movement of rotation on said bar and having a tongue and groove connection therewith whereby relative rotary movement between said stops and bar is limited, and non-rotary washers interposed between the stops.

8. A stop bar for tabulating machines comprising a bar circular in cross section having a longitudinal groove formed therein, a se-

ries of stops mounted to rotate on said bar each provided with a lug adapted to enter the groove, but of less width than the width of the groove, and washers interposed between the stops each having a lug adapted to enter and fit the groove.

9. In a typewriting machine and in a tabulating mechanism, the combination of a carriage, carriage feeding mechanism, a stop mounted on the frame of the machine and movable lengthwise of the carriage; a stop on the carriage normally out of line with the first recited stop, and mechanism adapted at a single operation to move the stop on the carriage into line with the stop on the frame and to move the stop on the frame lengthwise of the carriage.

10. In a typewriting machine, the combination of a carriage, carriage feeding mechanism, a bar mounted on the frame of the machine, a stop arranged on said bar to define a columnar field, means for moving said bar longitudinally in order to bring the stop thereon to any selected one of a plurality of denominational positions in the columnar field, a stop mounted on the carriage and normally out of line with the first recited stop, means for moving said carriage stop into position to co-operate with said first recited stop, and means for releasing the carriage from said carriage feeding mechanism, the bar-moving, carriage-stop-moving and carriage-releasing means operating concurrently.

11. In a typewriting machine, the combination of a carriage, carriage feeding mechanism, a bar mounted on the frame of the machine, a stop arranged on said bar to define a columnar field, means for moving said bar longitudinally in order to bring the stop thereon to any selected one of a plurality of denominational positions in the columnar field, a stop mounted on the carriage and normally out of line with the first recited stop, means for moving said carriage stop into line with said first recited stop, means for releasing the carriage from said carriage feeding mechanism, and a plurality of keys, each adapted when actuated to operate the means for moving said stop bar, the means for moving said carriage stop and the means for releasing said carriage.

12. In a typewriting machine, the combination of a carriage, carriage escapement mechanism comprising a rack and pinion, a stop rack-bar slidably mounted on the frame of the machine, a column stop adjustably mounted on said bar, a carriage stop pivoted on said carriage and normally out of line with said column stop, a differential cam plate operable to move said rack-bar predetermined extents lengthwise of said carriage, and a plurality of key levers each operable on said cam plate, each of said key levers being

also adapted to move said carriage stop to operative position and to separate said rack and pinion to release the carriage.

13. In a typewriting machine, the combination of a stop bar mounted on the frame of the machine, a column stop on said stop bar, means for moving said stop bar longitudinally, a carriage, escapement mechanism for controlling the feed of the carriage, means for releasing the carriage from the escapement mechanism, a movable stop on the carriage normally out of line with the column stop, means for moving the movable carriage stop into position to engage the column stop, and a key adapted to operate the means for moving the stop bar, the means for releasing the carriage from the escapement mechanism, and the means for moving the carriage stop into operative position.

14. In a typewriting machine, the combination of a stop bar mounted on the frame of the machine, a column stop thereon, means for moving said stop bar longitudinally, a carriage, an escapement mechanism therefor, means for releasing the carriage from the escapement mechanism, a movable stop on said carriage normally out of line with the column stop, means for moving the movable stop into position to engage the column stop, and a series of keys each adapted to operate the means for moving said stop bar, the means for releasing the carriage from its escapement mechanism and the means for moving the movable stop into position to engage the column stop.

15. In a typewriting machine, the combination of a stop bar mounted on the frame of the machine, a column stop thereon, means for moving said stop bar longitudinally different extents, a carriage, an escapement mechanism therefor, means for releasing the carriage from the escapement mechanism, a movable stop on the carriage normally out of line with the column stop, means for moving the movable stop into position to engage the column stop, and a plurality of keys each adapted to move said stop bar a predetermined distance, to release said carriage from its escapement mechanism and to move said movable stop into position to engage said column stop.

16. In a typewriting machine, the combination of a carriage, a tabulator stop pivotally mounted on said carriage, one or more column stops mounted on the fixed framework of the machine, a rocking member mounted on the main frame of the machine and with its axis of motion fixed and parallel with the travel of the carriage and having an eccentric part fixed to it and maintained at all times in a fixed relation with said rocking member as a whole, said eccentric part being adapted when said rocking member is rocked

to move said tabulator stop into position to engage one of said column stops, and a key for controlling said rocking member.

17. In a typewriting machine, the combination of a carriage, a tabulator bar mounted on the fixed framework of the machine, one or more column stops mounted on said tabulator bar, a tabulator stop movably mounted on said carriage, a member mounted on the main frame of the machine and adapted to rock about a fixed horizontal axis and having an eccentric part adapted when said member is rocked to engage said movable tabulator stop and to move it into position to engage one of said column stops said eccentric part being fixed to and having an unvarying relation with said rocking member as a whole, and a key for controlling said rocking member.

18. In a typewriting machine, the combination of a carriage, a tabulator bar mounted on the fixed framework of the machine, one or more column stops mounted on said tabulator bar, a tabulator stop movably mounted on said carriage, a rocking member mounted on the main frame of the machine and with its axis of motion fixed and parallel to the travel of the carriage and having an eccentric part adapted when said rocking member is rocked to engage said pivoted tabulator stop and to move it into position to engage one of said column stops said eccentric part being fixed to and having an unvarying relation with said rocking member as a whole, a key for controlling said rocking member, and a carriage release device operated by said key.

19. In a typewriting machine and in a tabulating mechanism, the combination of a carriage, a tabulator stop movably mounted on said carriage, a column stop bar mounted on the fixed framework of the machine, one or more column stops on said bar, a rocking member pivoted below and independently of said movable tabulator stop with its axis of motion fixed and parallel with the direction of movement of the carriage and having a fixed part adapted when rocked to move said stop into position to engage said column stop or stops, a key operatively connected with said rocking member, and a carriage release device operated by said key.

20. In a tabulating mechanism for typewriting machines, the combination with co-operative tabulating stops, of a rod or bar having rotary motion about a fixed axis and extending in the direction of the travel of the carriage, said tabulating stops being mounted independently of said rod or bar; and a key pivoted to a fixed part and operative to actuate said rod or bar, the latter operating to move certain of said tabulating stops to operative position.

21. In a tabulating mechanism for typewriting machines, the combination with co-

operative tabulating stops, of a rod or bar having rotary motion about a fixed axis and extending in the direction of the travel of the carriage, and a set of tabulating keys mounted on the frame of the machine and each operative to actuate said rod or bar, the latter when operated being effective to move certain of said tabulating stops to operative position, said tabulating stops being mounted independently of said rod or bar.

22. In a typewriting machine and in a tabulating mechanism, the combination of a carriage, step-by-step carriage feeding mechanism, a stop on the carriage, a stop on the machine frame, said stops being normally out of line with each other, means for moving both said stops to positions where they will co-operate when the carriage is released or freed from the control of said step-by-step feeding mechanism, and a key for actuating said means prior to the release of said carriage.

23. In a typewriting machine and in a tabulating mechanism, the combination of a carriage, step-by-step carriage feeding mechanism, a stop on the carriage, a stop on the machine frame, said stops being normally out of line with each other, mechanism for moving one of said stops into position to co-operate with the other stop, mechanism for moving said other stop so that it will co-operate with the first stop to arrest the carriage at a predetermined denominational position when said carriage is released from the control of said step-by-step feeding mechanism, and a key operative to actuate both said mechanisms.

24. In a typewriting machine and in a tabulating mechanism, the combination of a carriage, step-by-step carriage feeding mechanism, a stop on the carriage, a stop on the machine frame, said stops being normally out of line with each other, mechanism for moving one of said stops into position to co-operate with the other stop, differential mechanism for moving said other stop different predetermined extents for different denominational positions, and a plurality of keys each operative to actuate both said mechanisms.

25. In a typewriting machine and in a tabulating mechanism, the combination of a carriage, step-by-step carriage feeding mechanism, a carriage stop, a co-operative stop on the machine frame, said stops being normally out of line with each other, mechanism for moving said carriage stop into line with said co-operative stop, mechanism for moving said co-operative stop so that it will co-operate with the carriage stop to arrest the carriage at a predetermined denominational position when said carriage is released from the control of said step-by-step feeding mechanism, and a key operative to actuate both said mechanisms.

26. In a typewriting machine and in a tabu-

lating mechanism, the combination of a carriage, step-by-step carriage feeding mechanism, a carriage stop, a co-operative stop on the machine frame, said stops being normally out of line with each other, mechanism for moving said carriage stop into line with said co-operative stop, differential mechanism for moving said co-operative stop different predetermined extents for different 10 denominational positions, and a plurality of keys each operative to actuate both said mechanisms.

27. In a typewriting machine and in a tabulating mechanism, the combination of a carriage, step-by-step carriage feeding mechanism, a stop on the carriage, a stop on the machine frame, said stops being normally out of line with each other, means for moving both said stops to positions where they will co-operate when the carriage is released or freed 20 from the control of said step-by-step feeding mechanism, devices for releasing or freeing the carriage from the control of its step-by-step feeding mechanism, and a key for actuating 25 said means and said devices.

28. In a typewriting machine and in a tabulating mechanism, the combination of a carriage, step-by-step carriage feeding mechanism, a stop on the carriage, a stop on the machine frame, said stops being normally out of line with each other, mechanism for moving one of said stops into position to co-operate with the other stop, mechanism for moving said other stop so that it will co-operate with the first stop to arrest the carriage at a predetermined denominational position when said carriage is released from the control of said step-by-step feeding mechanism, devices for releasing the carriage from 35 the control of its step-by-step feeding mechanism, and a key operative to actuate both said mechanisms, said key being also operative to actuate the carriage releasing devices.

29. In a typewriting machine and in a tabulating mechanism, the combination of a carriage, step-by-step carriage feeding mechanism, a stop on the carriage, a stop on the machine frame, said stops being normally out of line with each other, mechanism for moving one of said stops into position to co-op-

erate with the other stop, differential mechanism for moving said other stop different predetermined extents for different denominational positions, devices for releasing the carriage from the control of its step-by-step feeding mechanism, and a plurality of keys and each also operative to actuate both said mechanisms and also operative to actuate the carriage releasing devices.

30. In a typewriting machine and in a tabulating mechanism, the combination of a carriage, step-by-step carriage feeding mechanism, a carriage stop, a co-operative stop on the machine frame, said stops being normally out of line with each other, mechanism for moving said carriage stop into line with said co-operative stop, mechanism for moving said co-operative stop so that it will co-operate with the carriage stop to arrest the carriage at a predetermined denominational position when said carriage is released from the control of said step-by-step feeding mechanism, devices for releasing the carriage from the control of its step-by-step feeding mechanisms, and a key operative to actuate both 75 said mechanisms, said key being also operative to actuate the carriage releasing devices.

31. In a typewriting machine and in a tabulating mechanism, the combination of a carriage, step-by-step carriage feeding mechanism, a carriage stop, a co-operative stop on the machine frame, said stops being normally out of line with each other, mechanism for moving said carriage stop into line with said co-operative stop, differential mechanism for moving said co-operative stop different predetermined extents for different denominational positions, devices for releasing the carriage from the control of its step-by-step feeding mechanism, and a plurality of keys each operative to actuate both 80 said mechanisms each of said keys being also operative to actuate the carriage releasing devices.

In testimony whereof I affix my signature, 95
in presence of two witnesses.

EMILE LECOULTRE.
